UNITED STATES PATENT OFFICE.

CHARLES H. WEISKOPF, OF HAWTHORNE, CALIFORNIA, ASSIGNOR TO INTERNATIONAL PRECIPITATION COMPANY, OF LOS ANGELES, CALIFORNIA, A CORPORATION OF CALIFORNIA.

APPARATUS FOR ELECTRICAL PRECIPITATION OF SUSPENDED MATERIAL FROM GASES.

Application filed April 13, 1925. Serial No. 22,849.

To all whom it may concern:

Be it known that I, CHARLES H. WEISKOPF, a citizen of the United States, residing at Hawthorne, county of Los Angeles, State of California, have invented a new and useful Improvement in Apparatus for Electrical Precipitation of Suspended Material from Gases, of which the following is a specification.

10 This invention relates to apparatus for electrical precipitation of suspended material, such as dust, fume, mist, etc., from gases containing the same and particularly to apparatus for this purpose in which the collecting electrodes are formed of concrete or other cement composition, or similar material of a semi-conducting nature. The main object of the present invention is to provide for the construction of such collecting electrodes in the form of sections and at the same time provide for effective supporting and re-enforcing of such sections and also for effective distribution of electrical potential to all parts of the electrode. A further object of the invention is to provide re-enforcing means in each electrode section, said re-enforcing means being of such nature that when the sections are assembled, said means co-operate to constitute continuous re-enforcing and electrical distributing means extending throughout the several sections of each electrode. A further object of the invention is to provide alternate sections of a collecting electrode 35 of the type above described with re-enforcing and electrical conducting means adapted to engage one another upon assembly of the sections in such manner as to properly align the sections and to prevent relative horizontal displacement of said sections and thus provide effective re-enforcing and supporting means for the entire electrode.

40 The accompanying drawings illustrate embodiments of my invention, and referring thereto:

Fig. 1 is a longitudinal vertical section through an electrical precipitator embodying my invention and provided with collecting electrodes comprising horizontally extending sections.

Fig. 2 is a transverse vertical section of the precipitator shown in Fig. 1.

Fig. 3 is an enlarged longitudinal vertical section of a portion of one of the collecting electrodes.

Fig. 4 is a horizontal section on line 4—4 in Fig. 3.

Fig. 5 is a fragmentary longitudinal vertical section through a sectional collecting electrode showing a modified means of engagement between the re-enforcing and conducting means in adjacent sections.

Fig. 6 is a partial longitudinal section through a collecting electrode comprising vertically extending sections.

Figs. 7 and 8 are partial longitudinal sections through collecting electrodes built up of smaller sectional units in which the divisions between sections extend both horizontally and vertically.

In the electrical precipitator shown in Figs. 1 and 2 the precipitator chamber or housing indicated at 1 is provided with suitable inlet means 2 and outlet means 3 for passage of gas therethrough and with means at the bottom such as hopper 4 adapted to receive precipitated material and having any suitable means for removal of such material therefrom. The entire structure comprising housing 1, inlet and outlet means 2 and 3 and hopper 4, is shown as constructed of concrete, and while this is not essential, my invention is particularly adapted for use in connection with this type of construction. Within chamber 1 are provided a plurality of discharge electrodes 5 of relatively small cross-section, small surface area, and sharp curvature, and collecting electrodes 6 having a relatively extended and substantially flat surface. In the form of the invention shown in these figures the collecting electrodes extend vertically so as to provide passages 7 between said electrodes through which the gas to be treated is passed in a horizontal direction. Furthermore the discharge electrodes 5 are shown as comprising wires or small rods extending in a vertical direction within the passages 7 between the collecting electrodes. It will of course be understood however that my invention is

100

not limited to this particular type of construction as many modifications may be made in the relative disposition of the electrode means and the gas may be passed in a vertical instead of a horizontal direction through the precipitator.

The vertical discharge wires 5 may be supported in any suitable manner by upper and lower supporting and spacing bars 8 and 9, 10 said bars being mounted on suitable supporting frames comprising for example horizontal frame members 10 and vertical frame members 11. Said supporting frames are in turn supported for example by supporting 15 means 12 mounted on suitable insulating supports 13 in the usual manner of such apparatus. Suitable means, such as weights 14, may also be provided for tensioning the discharge wires and keeping them in alignment.

Each of the collecting electrodes 6 is shown as comprising a plurality of superposed horizontal plate sections 15 mounted one above another so as to form a collecting 20 plate of relatively extended surface and provided with suitable supporting and re-enforcing means as hereinafter described. Such sections may be made of Portland cement concrete, or other cement or plaster 25 compositions, or terra cotta, transite, etc., or other semi-conducting material. If desired, the adjacent sections may be held in alignment at their adjoining edges by means of a tongue and groove construction or in any 30 other suitable manner, and I also prefer to secure said sections together by means of a cement grout or mortar which thoroughly fills the spaces between adjoining sections, so as to provide in effect a monolithic plate, 35 and prevent exposure of the re-enforcing members. The lowermost one of said sections of each collecting electrode preferably constitutes a supporting base section as indicated at 16, said base section being preferentially provided with horizontal embedded re-enforcing means indicated at 17 so as to provide increased horizontal strength in such member and enable it to effectively support the upper sections. Said base section 16 is 40 suitably supported for example by resting at its ends on the precipitator chamber or housing as indicated at 18. The horizontal sections 15 may be maintained in place and supported against lateral movement by 45 means of suitable side frames such as channel irons 20, said channel irons being mounted for example on beams or angle irons 21.

All of the materials above described, which 50 I contemplate using in the construction of the collecting electrode sections, are such as to require re-enforcing or strengthening, and are also of such relatively low electrical conductivity as to prevent effective and uniform distribution of electrical potential to

all parts of an electrode of large size formed solely of such material. In order to provide for more effective support and re-enforcing of the collecting electrode means and also provide for proper distribution of electrical 70 potential throughout said means, I therefore prefer to provide the horizontal sections 15 with metallic conducting and re-enforcing members extending parallel to the discharge wires and spaced at suitable intervals 75 throughout the length of each section. For this purpose I may in some cases provide alternate sections with vertical conducting and re-enforcing means 23 and 24 respectively,

said means in the adjacent sections 80 being in alignment with one another and adapted to engage one another so as to prevent relative lateral displacement of the sections. For example as shown in Figs. 1 to 3 the members 23 may comprise metallic tubular members and the members 24 may

comprise metal rods whose ends are adapted to enter within or engage the ends of the tubular members 23 as indicated at 25. Said rods 24 are preferably adapted to fit fairly closely within the tubular members 23 so as to provide a rigid construction and at the same time ensure good electrical connection between the re-enforcing and conducting 90 means of adjacent sections.

The effect of this construction is therefore such as to provide when assembled substantially continuous re-enforcing and conducting means extending throughout the more active portion of the collecting electrode. The expression "more active portion" is here understood to mean 100 the portion of the electrode above the base section 16 or in other words the portion of the collecting electrode which is provided with grounded embedded conducting members,

since the lack of grounded conducting members in the base section 16 will cause comparatively little electrical discharge between the discharge wires and said base section. The re-enforcing and conducting members 23 and 24 are embedded within the concrete electrode sections 15 and are preferably formed therein at the time of pouring such concrete sections in a similar manner to that

in which re-enforced concrete structural members are commonly made. It is highly desirable of course that said members be located centrally within the electrode sections so as to provide for the most effective re-enforcing and also provide uniform distribution of electrical potential to both faces of the electrode. I prefer in general to metallically ground all of the re-enforcing and conducting members 23 and 24, for example

by connecting all of said members to a wire or other conducting member 27 which is grounded as indicated at 28. Said grounded wire 27 may be omitted in some cases, however, so that the re-enforcing and conducting members are not metallically grounded

but are grounded only through the concrete housing 1. Said members serve in this case also, however, to preserve substantially uniform electrical potential throughout the plates. The horizontal re-enforcing member 17 in the lower or base section 16 is preferably not grounded, however, so that such base section is substantially or comparatively inactive electrically, and serves only to support the upper or active sections.

Suitable means are provided for supplying high electrical potential to the supporting electrode members and for this purpose the discharge electrode system may be connected by wire 29 to any suitable source of high tension current, either alternating or direct, but preferably rectified alternating high tension current, the other side of which source is grounded. Said source of high tension current is preferably adapted to maintain a potential difference between the discharge electrodes and the grounded collecting electrodes of from say 15000 to 100000 volts, the exact voltage required in any case depending upon the spacing of the electrodes and upon other conditions.

Instead of providing the alternate sections respectively with re-enforcing members adapted to engage one another I may provide similar re-enforcing means in all of the sections and provide suitable fastening or engaging means for connecting said re-enforcing members together. For example as shown in Fig. 5 each of the sections 15 may be provided with tubular re-enforcing members 23 so disposed as to be in alignment with one another when the plates are assembled, and suitable metallic pins or dowels 30 may be provided, said dowels being adapted to enter within or engage the ends of two adjoining tubular members 23.

It will also be understood that the sections 15 may extend in a vertical direction instead of a horizontal direction for example as shown in Fig. 6, each collecting electrode may comprise a plurality of such vertically extending sections, each of said sections being provided with horizontally extending re-enforcing and conducting members 23 and 24 adapted to engage one another and constitute substantially continuous metallic re-enforcing and conducting means in the same manner as above described. It will be noted that in this case the embedded conducting members extend horizontally and I therefore prefer to provide horizontally extending discharge wires 5 in this case, so as to preserve the parallel relation between the embedded re-enforcing and conducting members and the discharge electrode means. This is not necessary in all cases, however, since I may in some cases use vertical discharge members together with horizontal embedded conductors or vice-versa.

As shown in Fig. 7 each collecting electrode may comprise a plurality of smaller sectional units 15, the divisions between such sectional units extending both horizontally and vertically. Such sectional units may in this case comprise concrete blocks or slabs of suitable size and shape and may be laid up in any suitable manner for example as shown in the usual manner of laying up a brick wall. As in the other cases above described each of the sections 15 is provided with embedded re-enforcing and conducting members such as tubular members 23 and rods 24 adapted to engage one another and to form when assembled continuous metallic conducting and re-enforcing means extending throughout the height of the electrode in one direction. A similar construction is shown in Fig. 8. In this case however the embedded conducting members extend horizontally instead of vertically and therefore constitute continuous re-enforcing and conducting members extending throughout the collecting electrode from side to side. It will be seen that in any case each section of the collecting electrode is composed of semi-conducting material such as concrete and is provided with one or more metallic conducting and re-enforcing members, said members being adapted to engage one another for the purposes above mentioned, when the sections are assembled.

In operation the electrode system is energized by connection to the source of high tension current as above described and by reason of the relatively small surface area and sharp curvature of the discharge electrodes and the relatively extended area of the collecting electrodes a silent electrical discharge is produced from the discharge electrodes to the collecting electrodes. The metallic conducting members such as 23 and 24 cause substantially uniform distribution of electrical potential throughout the collecting electrodes due to the fact that all parts of said electrodes are uniformly in contact with a grounded metallic conducting system. In order to obtain the maximum uniformity of distribution of the electrical field I prefer in some cases as shown to arrange the conducting and re-enforcing members in each collecting electrode in the portions of said electrode between the adjacent discharge electrodes, or in other words to stagger the discharge electrodes 5 and embedded conductors 23 and 24 from one end of the treater to the other. Such an arrangement provides an especially effective distribution of the electrical field due to the fact that each portion of the surface of the collecting electrode which is in closest proximity to an embedded conductor is at a maximum distance from the discharge member and vice versa. The electrical field is there-

fore maintained with maximum uniformity over substantially the entire surface of the collecting electrode.

The gas to be treated is passed through the chamber 1 so as to flow between the discharge electrodes and the collecting electrodes. Under the action of the electrical field the suspended particles carried by the gas become charged and are attracted to the collecting electrodes. The material so precipitated eventually falls off the collecting electrodes by gravity and is collected at the bottom of the precipitator. If desired the collecting electrodes may be jarred or rapped from time to time to dislodge deposited material therefrom, but it has been found with semi-conducting electrodes such as above described, the deposited material adheres to the collecting electrodes in a relatively loose manner and therefore falls off by its own weight before it becomes thick enough to seriously impair the effective operation of the precipitator.

What I claim is:

- 25 1. An apparatus for electrical precipitation of suspended material from gases containing the same comprising discharge electrode means and collecting electrode means, said discharge electrode means comprising members of relatively small cross-section extending parallel to one another, and said collecting electrode means comprising a plurality of plate sections of semi-conducting material, metallic re-enforcing and conducting members embedded in said semi-conducting material in each of said sections and extending parallel to said discharge electrode means, and said conducting and re-

enforcing members in adjacent sections engaging one another at their ends so as to provide continuous conducting and re-enforcing means for said collecting electrode. 40

2. An apparatus as set forth in claim 1, said conducting and re-enforcing members being in metallic connection with the ground. 45

3. A collecting electrode for electrical precipitators comprising a plurality of plate sections composed of semi-conducting material, metallic conducting and re-enforcing members embedded in each of said sections, said conducting and re-enforcing members in adjacent sections being in alignment and adapted to engage one another at their ends so as to constitute substantially continuous 50 re-enforcing and conducting members for said collecting electrode. 55

4. A collecting electrode for electrical precipitators as set forth in claim 3, said conducting and re-enforcing members being in 60 metallic connection with the ground.

5. A collecting electrode for electrical precipitators comprising a plurality of plate sections of semi-conducting material, metallic conducting and re-enforcing members embedded within each of said sections, said conducting and re-enforcing members in adjacent sections being adapted to engage one another at their ends in such manner as to prevent relative lateral displacement of 65 said sections and also provide electrical connection between said sections. 70

In testimony whereof I have hereunto subscribed my name this 19th day of March, 1925.

CHARLES H. WEISKOPF.
